SEWING MACHINE

Grant G. Gilbertson, Milwaukee, Wis.

Application February 9, 1940, Serial No. 318,026

2 Claims. (Cl. 112—210)

This invention relates generally to sewing machines, and more particularly to a stitch regulating and reversing mechanism.

At the present time, many conventional sewing machines are equipped with a stitch regulator, but have no provision for reversing the feed of material. Therefore, the invention has primarily for its object to provide an exceedingly simple and inexpensive stitch regulating and reversing mechanism.

While the present invention may be incorporated in sewing machines as standard equipment, the same is designed particularly as a replacement for present stitch regulators, whereby the feed mechanism may be reversed for darning and similar sewing operations.

Incidental to the foregoing, a more specific object of the invention resides in the provision of a stitch regulator including manually reciprocal means for quickly reversing the feed mechanism, without affecting the stitch.

Another object resides in the provision of resilient means for holding the regulator and reversing block in its adjusted set positions.

Another object is to provide a mechanism of the foregoing type for replacing the standard stitch regulator with which conventional sewing machines are now equipped, and which requires no change in the structure of the machine.

With the above and other objects in view, which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing:

Figure 1 is a vertical section through the column of a conventional sewing machine equipped with the present invention, the view being taken on the line 1—1 of Figure 2;

Figure 2 is a sectional view taken on the line 2—2 of Figure 1; and

Figure 3 is a fragmentary section illustrating a conventional stitch regulating mechanism to be replaced by the present invention.

Referring now more particularly to the ac-

companying drawing, the numeral 1 designates a plate provided with a vertical column 2 that carries an overhead arm 3.

Journaled in the column 2 is a driven shaft 4, upon which an eccentric cam 5 is secured. Mounted within the column is a reciprocative arm 6, bifurcated at its upper end for reception of the cam 5, and connected at its lower end to an arm 7 secured to a rocker shaft 8, which actuates a conventional feed mechanism (not shown).

Pivottally mounted on a stud 9, threaded in the column 2, is a longitudinally grooved guide block 10 for reception of a roller 11 carried by the arm 6. For the purpose of adjustment, the roller 11 is mounted on an eccentric electric pin 12 carried by a disc 13 provided with a threaded stud 14, extending through the arm 6 and secured in adjusted position by a nut 15. Threaded into the column 2 is a sleeve 16, which carries a slidable shank 17, threaded at its outer end for reception of a thumb-nut 18, providing for adjustment and reciprocation of the shank within the sleeve 16.

Slidably mounted in the back of the grooved block 10 is an arm 19, terminating in a lateral finger 20, which passes through the end of the shank 17. A spring 21, mounted on the arm 19 between the block 10 and shank 17, serves to releasably hold the block 10 and shank 17 in their relative set positions.

In the position of the parts illustrated in Figure 1, the spring 21 urges the shank 17, which is slidably journaled in the sleeve 16, to its retracted position, in which the thumbnut 18 engages the end of the sleeve. When the shank 17 is withdrawn to shift the angle of the block 10 for reversing the direction of feed, the spring 21, after passing over center, then urges and holds the shank in its projected position. If it were not for the spring 21, action of the roller 11 within the guide block 10 might readily shift the angle position of the block 10 and the shank 17 within the sleeve 16.

In operation, the angle of the grooved block 10 is varied by adjustment of the thumb-nut 18. Obviously, as the angle of the groove is reduced, reciprocal movement of the arm 6 is correspondingly reduced, thus imparting shorter movement to the rocker shaft 8 which actuates the feeding mechanism, and, consequently, reducing the length of the stitch.

When it is desired to reverse the feeding mechanism, the thumb-nut 18 and shank 17 are pulled outwardly until the arm 20 abuts the in-

5   ner end of the sleeve 16, thus reversing the angle of the groove and the rocking operation of the shaft 8 with relation to the vertical movement of the conventional feeding mechanism (not shown). When the shank 17 is in its withdrawn position, the length of the stitch is regulated by adjustment of the sleeve 16, the inner end of which is engaged by the arm 19.

10   Figure 3 illustrates standard stitch regulating mechanism with which many sewing machines are now equipped, and comprises a thumbscrew 22 threaded in the column 2, and provided at its inner end with an annular groove 23 for reception of a lug 24 carried by an ear 25 extending 15 from the grooved block 10'. These parts are removed and replaced with the block 19, the threaded sleeve 16, and the shank 17, comprising the present invention; thus converting old types of machines to provide for reversing of feed, and, 20 consequently, the direction of stitching.

15   From the foregoing explanation considered in connection with the accompanying drawing, it will be seen that an exceedingly simple and inexpensive mechanism has been provided for both 25 regulating and quickly reversing the direction of feed in a sewing machine, thus materially facilitating the operation of darning and the like without the necessity of an awkward operation in turning the goods to be stitched, as required 30 by present conventional machines not equipped with a reversing feed mechanism.

I claim:

1. In a sewing machine including a hollow column, a driven shaft journaled in said column, 35 and an oscillating and reciprocative arm opera-

tively connected with said shaft for actuating a feed mechanism; a stitch regulating and reversing mechanism mounted in said column and comprising, a guide block pivotally mounted in the column for effecting longitudinal reciprocative movement of said arm during oscillation imparted thereto by said driven shaft, a sleeve threaded in said column, an adjustable shank 5 slidably mounted in said sleeve, an arm connecting said block and shank, and resilient means 10 for releasably holding said block in adjusted position.

2. In a sewing machine including a hollow column, a driven shaft journaled in said column, a cam mounted on said shaft, and an oscillating 15 and reciprocative arm actuated by said cam; a stitch regulating and reversing mechanism mounted in said column and comprising, a grooved guide block pivotally mounted in the column, a roller carried by said arm and longitudinally movable in the groove of said guide block for effecting longitudinal reciprocative movement of said arm during oscillation imparted thereto by said cam, a sleeve threaded in 20 said column, a shank slidably mounted in said sleeve, a thumb-nut threaded on the outer end of said shank for manual longitudinal adjustment and shifting of said shank within the sleeve, an arm slidably carried by said guide block and 25 pivotally connected to the inner end of said shank, and a coiled spring mounted on said arm for releasably retaining said block in adjusted and 30 set positions.

GRANT G. GILBERTSON. 35
